UNITED STATES PATENT OFFICE.

FELIX J. RUSH, OF NEW YORK, N. Y.

INSECT-GUARD.

1,164,219.

Specification of Letters Patent. Patented Dec. 14, 1915.

Application filed December 7, 1914. Serial No. 875,764.

To all whom it may concern:

Be it known that I, FELIX J. RUSH, a citizen of the United States, residing in the borough of Manhattan, city, county, and State of New York, have invented a new and useful Improvement in Insect-Guards, of which the following is a description.

This invention relates to insect guards and particularly to devices calculated to prevent the insects from climbing table legs and the legs of other articles of furniture.

Among the objects of my invention may be noted the following: to provide means by which insects will be prevented from climbing the legs of furniture; to provide means which will act as a deterrent to the progress of insects in attempting to climb the legs of furniture; and to provide a simple, compact, strong device which is cheap to produce and quite durable for accomplishing the purposes stated.

With the above objects in view and others which will be detailed during the course of this description, my invention consists in the parts, features, elements and the combinations thereof hereinafter described and claimed.

In order that my invention may be clearly understood I have provided drawings wherein:

Figure 1 is a perspective view of the lower portion of the leg of an article of furniture with my invention applied thereto; Fig. 2 is a perspective of one form of my device; Fig. 3 is a central vertical section of the structure of Fig. 2; and Fig. 4 is a section similar to Fig. 3 showing another form of my invention.

Referring to the drawings, the numeral 1 indicates the leg of an article of furniture such as a bed which, as usual, is, or may be, provided with a caster 2 of ordinary construction. The trim of the lower portion of the leg is indicated by 3.

According to my invention the guard comprises the member 4 which, in the form of Figs. 2 and 3, is substantially cylindrical and made in the form of a ring having in its inner periphery an angular groove 5, in which is set a diaphragm or central member 6 provided with an aperture 7. The member 4 is preferably made of glass or other material having similar characteristics; that is to say, a material which is, or may be, provided with a perfectly

smooth surface affording no foothold for the insects, and over which they cannot crawl owing to the smoothness of the surface of said member. After considerable experimentation, I have found that such a member 60 operates as an absolute deterrent or guard against the passage of insects, in consequence of which, I desire to lay stress upon both the form and the material of the member 4, viz: that its surface and form are such as 65 to prevent the insects from crawling thereover.

The material of the inner or central member 6 is, preferably, of a quality enabling it to seal connection between the same 70 and the member 4 in the groove 5, and for this purpose I have found that felt, rubber and leather are efficacious, and in applying the same I crowd or compact the same into the groove 5 of the member 4, as 75 indicated by the heavy indications adjacent the groove 5. Moreover, such materials enable the guard to be properly applied to the leg of the furniture without injuring or engagement between the member 4 and the 80 leg, and frictionally retain the member in the event casters or other terminal devices are not applied to or formed on the leg. Moreover, the aperture 7 may be of any desired shape, and the material of the member 85 6 will, when the guard is applied, crowd around, or closely cling, to the leg 1 so as to prevent the passage of the insects between the latter and the member 6.

In the form of my invention shown in 90 Fig. 4, the member 4 is rectangular in form, so as to provide thereby corners or edges 8 which also act as barriers to the passage of the insects, it being found by experimentation that sharp edge thus presented prevent 95 the insects from turning angles. In addition, the smooth or glazed surfaces of the member 4 operate as described.

I desire it understood that my invention is not confined to the use of glass for the member 4, as any material may be used, the surface of which can be made smooth and slippery or glazed, and providing that the character of the surface will not be altered by changes in temperature or atmospheric 105 conditions.

Having thus described my invention, what I claim and desire to secure by Letters Patent is:

An insect guard comprising a member 110

composed of glass and having a central aperture, the wall about the aperture being grooved; in combination with a central attaching disk-like member of elastic material, 5 having its periphery compressed within said groove and having a central aperture.

In testimony whereof I have hereunto

signed my name in the presence of two subscribing witnesses.

FELIX J. RUSH.
